Primary Examiner — Mary Ann Calabrese(74) Attorney, Agent, or Firm — John M. Lipchitz; Kevin C. Johnson; Steven W. Miller(57) CLAIM

The ornamental design for a label for a shaving razor, as shown and described.

DESCRIPTION

FIG. 1 is a perspective view of a label for a shaving razor showing my new design;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a rear view thereof.

The broken lines are directed to the environment and are for illustrative purposes only and form no part of the claimed design.
